UNITED STATES PATENT OFFICE.

GREGORY JOHN SPOHRER, OF FRANKLIN, PENNSYLVANIA, ASSIGNOR, BY MESNE ASSIGNMENTS, TO THE MOTOR COMPRESSOR COMPANY, OF WILMINGTON, DELAWARE, A CORPORATION OF DELAWARE.

STARTING MECHANISM FOR INTERNAL-COMBUSTION ENGINES.

1,178,603.

Specification of Letters Patent.

Patented Apr. 11, 1916.

Application filed March 25, 1913. Serial No. 756,769.

To all whom it may concern:

Be it known that I, GREGORY J. SPOHRER, a citizen of the United States, residing at Franklin, in the county of Venango and 5 State of Pennsylvania, have invented a new and useful Starting Mechanism for Internal-Combustion Engines, of which the following is a specification.

This invention relates to starting mechanism 10 for internal combustion engines of the type employing a convertible motor-compressor adapted to be connected to the shaft of the engine so as to drive that shaft in starting the engine and be driven by the 15 engine shaft in order to compress air and store it in a tank from which air under pressure may be drawn as required for operating the motor-compressor as a motor.

The invention relates more particularly 20 to the mechanism employed for connecting the motor-compressor to the shaft of the engine or an auxiliary shaft connected thereto. Such a connecting mechanism constructed in accordance with the present invention 25 is of special utility in connection with starting mechanism for internal combustion engines of the type disclosed in an application for patent filed by me June 12, 1914, and serially numbered 811,579.

30 In most forms of internal combustion engines, particularly those employed on automobiles, the engine shaft rotates always in the same direction. A motor-compressor for use in starting such an engine, however, is 35 preferably arranged to have its shaft rotate in one direction when operating as a motor and in the opposite direction when operating as a compressor. Also, it is desirable that when the motor-compressor is operating as 40 a motor, its shaft should rotate at a higher speed than that at which the engine shaft is rotated, whereas when the engine is running and ample power is available for driving the motor-compressor as a compressor, the 45 shaft of the compressor may be connected directly to the engine shaft so that the two rotate at the same speed.

In accordance with the present invention, 50 a mechanism is provided for connecting a convertible motor-compressor to a shaft which is adapted to drive and be driven by the motor-compressor such that when the shaft is driving the motor-compressor to compress and store air, the shaft of the com-

pressor will be connected directly to the 55 power-shaft so that the two will rotate in the same direction and at the same speed, and such that when the motor-compressor is operating as a motor, it will be connected to the driven shaft through speed-reducing 60 and reversing gearing whereby the two shafts will rotate in opposite directions and the driven shaft at a much lower speed than the shaft of the motor. The mechanism, whereby the shaft of the motor-compressor 65 and the engine shaft are connected in these two different relations, is preferably arranged to be actuated in part by compressed air since a supply of compressed air is maintained for operation of the motor. For this 70 purpose, an air-piston may be employed moved in one direction by air drawn from the supply tank and in the opposite direction by a spring.

The invention will be better understood by 75 reference to the following description taken in connection with the accompanying drawings which show an embodiment of the invention.

In these drawings, Figure 1 is a view, partially diagrammatic, of a motor-compressor, an engine shaft connected thereto, a tank and connections from the tank to the motor-compressor; Fig. 2 is a top view of the motor-compressor and a portion of the engine-shaft; Fig. 3 is a section on line 3—3 of Fig. 2; Fig. 4 is a section on line 4—4 of Fig. 2; Fig. 5 is a section on line 5—5 of Fig. 2 with the cylinder of the motor-compressor in elevation and Figs. 6 to 10 are detail 80 views hereinafter referred to.

In the drawings, 1 indicates the shaft of the engine having a gear 2 thereon which is connected by a chain 3 with a gear 4 formed on a rotating drum 5. This drum has a 95 detachable-head 6 whose sleeve 6' is rotatable upon the outer end of the shaft 8 of the motor-compressor, a ball-bearing 7 being provided at the end of the sleeve 6' to receive the end thrust. The shaft 8 is shown as 100 provided with cranks 9 and 10 and its opposite end is received in a bushing 11 in a journal 12 formed in the casing 13 of the motor-compressor 14.

The motor-compressor shown in the drawings is of a two cylinder, double acting, compound type having a high pressure cylinder 15 and a low pressure cylinder 16.

The high pressure piston is shown at 17 connected by a piston-rod 19 and pin 20 to a connecting rod 22 on the crank 9. The end of the piston-rod 19 is adapted to reciprocate in guides 21. The piston 18 of the low pressure cylinder is connected by a rod 23 and pin 24 to the connecting rod 26 on the crank 10. The end of the piston-rod 23 is adapted to reciprocate in guides 25.

10 The valves of the motor-compressor are operated by two eccentrics 27 and 28 on the shaft 8 and the straps 29 and 30 of these eccentrics actuate rods 31 and 34 which are connected to the valves. The 15 valve for the low pressure cylinder is shown at 32; it includes a valve-member 55 mounted on a pin 54 secured in the body of the valve 32 and it is reciprocated within a cylinder 33 by the rod 31. The valve for the 20 high pressure cylinder is shown at 35 (Fig. 2) and is reciprocated within a cylinder 36 by the rod 34. The upper ends of the cylinders are closed by a detachable head 37 having a cooling chamber 38' therein and 25 the cylinders are provided with a water-jacket as shown at 38. The pistons and piston-rods are provided with suitable packing as shown at 46, 47, 48, 49, 51, 52 and 53.

30 The motor-compressor is connected to a tank 39 and in this connection is a controlling valve 41. From the tank, a pipe 40 leads to the valve and from the valve, a pipe 45 carries air to a coupling 43 leading to the high pressure valve chamber 36. From this 35 valve chamber, air enters the high pressure cylinder at one or the other end thereof, causes reciprocation of the piston therein, then passes to the low pressure valve chamber 33 and is admitted by the valve 32 through ports 56 and 57 and passages 58 and 59 to opposite ends of the low pressure cylinder 16 so as to cause reciprocation of the piston 18, after which the air from the 40 cylinder 16 is permitted to escape through an exhaust port E. When the motor-compressor is used as a compressor, air is drawn in at the port E and takes the reverse course 45 through the cylinders and valve to the tank 39.

50 The drum 5 constitutes the main transmission member for transmitting power between the motor-compressor and the engine shaft. At one end, this drum is contracted in diameter so as to form a sleeve 60 which is adapted to rotate upon a bushing 61 secured upon a journal 62 formed integral with and projecting from the casing of the motor-compressor. The wall 65 projecting from the casing of the motor-compressor 55 forms an annular chamber between it and the contracted portion 60 for the reception of an annulus 80 hereafter referred to and the edge 64 of the wall 65 is grooved to receive a packing 63 which coacts with the 60 drum 5 and serves as an oil retaining means.

The drum 5 has an internal gear 66 formed integral therewith and this gear meshes with a plurality of pinions 67 which also mesh with a gear 71 secured upon the shaft 8. The pinions 67 are mounted for rotation on pins 68 which project laterally from an annulus 69 whose sleeve 70 is adapted to rotate upon the bushing 61 between the portion 60 of the drum 5 and the pinions 67. Any desired number of pinions 67 may be employed; in the present instance, three such pinions are provided.

At times, the annulus 69 rotates relatively to the drum 5 and at other times, it is clutched to the drum so that the two rotate 70 together. This connection of drum 5 and annulus 69 is effected by a plurality of pins 78 which are movable parallel to the axis of shaft 8 in openings provided in the inwardly directed portion of drum 5 leading to the 80 sleeve 60. The ends of these pins are adapted to enter within or be withdrawn from holes provided for their reception in the annulus 69 as shown in Fig. 3. The pins 78 have enlarged heads which are received in a groove formed in the ring 80 lying in the space between the wall 65 of the casing and the portion 60 of drum 5. The pins 78 travel around shaft 8 with the drum 5 as the latter is rotated; the ring 80, however, 85 does not rotate, but it may be moved slightly in the direction of the axis of shaft 8 to carry the pins 78 into or out of coaction with annulus 69. To effect this movement of ring 80, the latter is provided with radially disposed studs 84, r and r' (Figs. 5, 9 and 10) which enter inclined slots 65' in the wall 65. The projection 84 is extended to form a handle 86 for turning ring 80 manually. The projection 84 also has a 90 socket formed therein to receive the spherical end of a piston 82 adapted to reciprocate in a cylinder 83, the piston being actuated in one direction by a spring 81 within the cylinder and in the other direction by compressed air admitted to the end of the cylinder through a pipe 85 leading from the 95 master-valve 42.

The annulus 69 is provided with means whereby it may rotate freely upon the bushing 61 in one direction and whereby any tendency of the annulus to rotate in the opposite direction upon the bushing 61 will be effectually checked. For this purpose, the annulus 69 is provided with a plurality of 100 slots 72 open to the interior of the annulus and disposed substantially at a tangent to the circle of the interior of the annulus. In each of these slots is a roller 73 contacting with the exterior of the bushing 61 and with 105 the opposite wall of the slot 72. Each of the rollers is acted upon by a spring-actuated rod 74 located in an opening in the annulus 69 and urged toward the roller 73 by a spring 75 whose tension may be adjusted by 110

means of a nut 76. With this form of connecting mechanism, the engine shaft may be driven from the motor-compressor shaft to start the engine and as soon as the engine is started, the parts actuated thereby may 5 rotate at the speed for which the engine is set independently of the motor-compressor mechanism. Also, the motor-compressor may be actuated in the opposite direction to 10 serve as a motor driven by the engine shaft to compress and store air. The connection between the motor-compressor and the power-driven shaft for use in operating the motor-compressor as a compressor is a 15 direct one causing simultaneous rotation of the power-driven shaft and the motor shaft in the same direction. But when the motor-compressor is operated as a motor, it is connected to the power shaft through a speed-reducing and reversing gear. The parts are 20 shown in Fig. 3 in the position they assume when the motor-compressor is used as a motor. The shaft 8 is then driven in a counter-clockwise direction turning the 25 pinions 67 in a clockwise direction and thus causing rotation of the drum 5 and the engine shaft 1 in a clockwise direction. When the pinions 67 are rotating thus and transmitting power from the motor to the rotary 30 member 5, they tend to cause rotation of the annulus 69 in the counter-clockwise direction, but such rotation of the annulus is precluded by the rollers 73 coacting with the bushing 61 and the walls of the slots 72 and 35 serving as a ratchet and pawl mechanism. At this time, the ring 80 is in the position shown in Fig. 3 with the pins 78 held out of the holes 69' in the annulus 69. The ring 80 is held in this position by the spring 81 40 of the pneumatic ram 83, which spring 81 turns the ring 80 to the position where the projections 84, r and r' thereon are at the ends of the slots 65' which are adjacent to the casing of the motor-compressor. The 45 parts are maintained in this position while the compressor runs as a motor to start the engine and when the engine is started, the rotary member 5 is continued in its clockwise rotation by the engine at a higher 50 speed than that at which it was driven by the motor, and the member 5 then causes the pinions 67 and annulus 69 to rotate in a clockwise direction about the bushing 61 and gear 71, such rotation of the annulus 69 in 55 a clockwise direction being permitted by the rollers 73. The supply of air to the motor may then be cut off and the shaft of the motor will come to rest.

When it is desired to operate the motor- 60 compressor as a compressor driven by the rotary member 5 and engine shaft 1, air is admitted to the ram 83 thereby shifting the handle 86 against the tension of spring 81 so that the projections 84, r and r' move to 65 the opposite ends of the slots 65' as shown

in Fig. 10, thus moving the ring 80 in the direction of the axis of shaft 8 and projecting the ends of pins 78 into the holes 69' in the annulus 69. This locks the annulus to the drum 5 so that the annulus and the 70 pinions 67 thereon rotate with the drum 5 and carry the gear 71 and shaft 8 with them, all of the parts then rotating in a clockwise direction and such rotation of annulus 69 being permitted by the rollers 73. 75

The appropriate air connections are made as follows, reference being made to Figs. 1 and 7. The neutral position of the valve is that indicated by the letter M, with the handle extending to the left in Fig. 1. To 80 compress air in the tank, the handle is turned up as shown in Fig. 1. If there be no supply of compressed air in the tank, the handle 86 is operated manually, but if there be a supply, when handle 100 is turned up as shown 85 in Fig. 1, air will flow from the tank 39 through pipe 85 to cylinder 83 and operate lever 86 pneumatically. When the mechanism is driven as an air-compressor by the engine, air will flow from the compressor 90 through pipe 45, port 97, passage 96 past check-valve 102 to chamber 90, port 101, and port 104 to pipe 40 and tank 39. When sufficient air has been compressed, the handle is moved to the neutral position M and a vent 95 e is brought opposite the end of pipe 85 to allow air to escape from cylinder 83 so that the lever 86 will be returned to its normal position by spring 81.

To operate as a motor, the handle is 100 turned down to the position M' and air flows from tank 39 and pipe 40 to port 104, port 107, chamber 90, port 103, port 99, passage 98, port 97 and pipe 45 to the high pressure cylinder. Should the high pressure crank 105 be on dead center, the handle 100 may be moved to the position M² intermediate the neutral position M and the position M' just referred to. Air would then flow to the chamber 90 as just described and from there to the port 103, port 105 and pipe 42 to the low pressure cylinder and as soon as the high pressure crank was shifted off center, the handle would be moved to the position M' 110 for operating the motor-compressor as a 115 compound motor.

The member 5 of the gearing connecting the motor-compressor with the power-shaft is shown as connected to that shaft by a chain; it will be apparent, however, that the 120 power-shaft and the motor-compressor shaft might be in alinement in which case the rotary member 5 could be secured directly to the engine-shaft.

What I claim is:

1. The combination with a convertible motor-compressor and an engine shaft adapted to drive and be driven by the same, of a gear on the shaft of the motor-compressor, an internal gear connected with the en- 125 130

gine shaft, a plurality of pinions meshing with said gears, a rotatable support for said pinions and automatic means for permitting or preventing rotation of said rotatable support dependent upon the relative speeds of the engine shaft and the motor-compressor; substantially as described.

2. The combination with a convertible motor-compressor and an engine shaft 10 adapted to drive and be driven by the same, of a gear on the shaft of the motor-compressor, an internal gear connected to the shaft of the engine, a plurality of pinions meshing with said gears, a rotatable support 15 for said pinions and automatic clutch mechanism for preventing rotation of said support when the motor-compressor drives the engine and for permitting rotation of the support when the engine operates under its own power; substantially as described.

3. The combination with a convertible motor-compressor and an engine shaft adapted to drive and be driven by the same, of a gear on the shaft of the motor-compressor, an internal gear connected with the engine shaft, a plurality of pinions meshing with said gears, a rotatable support for said pinions and automatic devices for preventing rotation of said support when the motor-compressor drives the engine, said devices permitting free rotation of said support when the speed of said internal gear driven by the engine exceeds the speed of the other gear, substantially as described.

4. The combination of a shaft, a second shaft adapted to drive and be driven by the first shaft, a gear on the first shaft, an internal gear connected to the second shaft, a plurality of pinions meshing with said gears, a rotatable support for the pinions, an automatic mechanism for permitting rotation of said support in one direction and preventing rotation of the support in the opposite direction, and means for locking said support to said internal gear; substantially as described.

5. The combination with a convertible motor compressor and an engine shaft adapted to drive and be driven by the same, of a gear on the shaft of the motor compressor, an internal gear connected with the engine shaft, a plurality of pinions meshing with said gears, a rotatable support for said pinions, automatic means for preventing rotation of said support when the motor compressor drives the engine and permitting rotation of the support when the engine operates under its own power, and means for locking said support to said internal gear to cause the engine to drive the motor compressor; substantially as described.

In testimony that I claim the foregoing as my own, I have hereto affixed my signature in the presence of two witnesses.

GREGORY JOHN SPOHRER.
